UNITED STATES PATENT OFFICE.

WILLIAM C. STICKLER, OF BELLE PLAINE, KANSAS.

CLAMP.

SPECIFICATION forming part of Letters Patent No. 377,693, dated February 7, 1888.

Application filed October 4, 1887. Serial No. 251,417. (No model.)

To all whom it may concern:

Be it known that I, WILLIAM C. STICKLER, a citizen of the United States of America, residing at Belle Plaine, in the county of Sumner and State of Kansas, have invented certain new and useful Improvements in Clamps, of which the following is a specification, reference being had therein to the accompanying drawings.

10 This invention pertains to certain new and useful improvements in clamps, having for its object the provision of simple and efficient means for securely holding a plowshare during the course of sharpening the same, whereby 15 the latter operation is rendered more easily and readily accomplished.

The invention consists in a suitably-shaped bar or arm having at one end clamping-arms for hugging the plowshare and a threaded rod 20 for tightly holding the same, substantially as hereinafter fully set forth, and particularly pointed out in the claims.

In the accompanying drawings, Figure 1 is a view in perspective showing my invention as 25 applied to a plowshare. Fig. 2 is a side elevation, and Figs. 3 and 4 are detail perspective views.

30 In carrying out my invention I employ a bar or arm, A, curved or bent at one end, and at the extreme upper widened end of the vertical portion of this bar or arm the same is provided with a threaded aperture. The other forward end of this arm or bar is provided with or has formed integral therewith an approximately 35 U-shaped bar, B, having two inwardly-inclined clamping-arms, b b, the same being slightly beveled rearwardly, as shown.

C is a screw-threaded rod passed through the before-referred-to aperture in the upper 40 widened end of the vertical portion of the bar or arm A, said rod being provided with a flattened outer end, as shown. To the forward inner end of this threaded rod C is secured a keeper-plate, D, provided with a

central normally horizontal groove, d, as 45 shown. This keeper-plate is loosely secured on the end of the rod C by projecting the narrow end of said rod through a central aperture in said plate, after which the same is clinched.

In practice the point of the plowshare is 50 passed through the U-shaped clamping-bar until the arms thereof bear tightly against the sides of said plowshare, (the bevel of said arms conforming to the bevel of the sides of said plowshare,) after which the rod C is turned 55 until the keeper-plate D comes in contact with the rear end of the horizontal portion of said plowshare, which end enters the groove d of said plate, and by turning said rod C the secure clamping of the plowshare is readily ef- 60 fected.

From what has been said it will be seen that my invention comprises simple and efficient means for securely clamping and securing a plowshare, whereby the same can be conveniently handled while being ground or sharpened. 65

I claim as my invention—

1. The herein-described clamp, comprising the bar or arm, the U-shaped clamping-bar, the threaded rod, and the keeper-plate, substantially as shown and described. 70

2. The combination, with the bar or arm, of the U-shaped bar having the inclined clamping-arms and the threaded rod carrying a keeper-plate, substantially as shown and described. 75

3. The combination, with the bar or arm having the bent end provided with an aperture, of the clamping-bar, the threaded rod, and the keeper-plate, substantially as shown and described. 80

In testimony whereof I affix my signature in presence of two witnesses.

WILLIAM C. STICKLER.
